United States Patent Office

Des. 216,524
Patented Jan. 27, 1970

216,524

TEXTILE FABRIC

Leonard C. Clementi, Huntington, N.Y., assignor to Cannon Mills Company, Kannapolis, N.C., a corporation of North Carolina

Filed Nov. 25, 1968, Ser. No. 14,621

Term of patent 14 years

Int. Cl. D5—02

U.S. Cl. D92—1

FIGURE 1 is a top plan view of a textile fabric showing my new design with the unit repeat being continuous from all sides; and

I claim:

The ornamental design for a textile fabric, substantially as shown and described.
